SURFACE ORNAMENTATION OF WALLS, &c.

No. 16,402.

Patented Dec. 1, 1885.

UNITED STATES PATENT OFFICE.

FREDERICK MANKEY, OF WILLIAMSPORT, PENNSYLVANIA.

DESIGN FOR SURFACE ORNAMENTATION OF WALLS, &c.

SPECIFICATION forming part of Design No. 16,402, dated December 1, 1885.

Application filed July 18, 1885. Serial No. 171,996. Term of patent 7 years.

To all whom it may concern:

Be it known that I, FREDERICK MANKEY, of Williamsport, Lycoming county, Pennsylvania, have invented and produced a new and original Design for Surface Ornamentation of Walls, &c., of which the following is a specification, reference being had to the accompanying photographs, forming part hereof.

Figure 1 shows a surface on which is formed to my design. Fig. 2 is a longitudinal section of said surface.

Similar letters of reference indicate like parts.

My design consists, first, in a row of elevations, A, extending longitudinally the surface, each elevation consisting in a quadrilateral rectangular lower portion surmounted by a pyramid, the base of which is a rectangle smaller than the aforesaid lower portion, and the sides of which are rounded or curved; second, a row of elevations, B, of substantially similar configuration, but elongated, as shown, and extending transversely across the surface; third, a row of elevations, C, similar to elevations A.

The elevations B are interposed between the elevations A and C and separated from said elevations by narrow longitudinal channels D. Narrow transverse channels E also separate the elevations, as shown.

The elongated elevations B exhibit a different grain-marking from the flat or channel portion of the surface.

I claim—

The design for surface ornamentation of walls, &c., substantially as herein shown and described, which consists in the longitudinal rows of transverse elevations A, B, and C, with intermediate channels, D and E, the elevations B being elongated and having a curved upper surface, and the said elevations showing on their upper sides a different grain-marking from that which appears in said channels.

FREDERICK MANKEY.
